UNITED STATES PATENT OFFICE.

JAMES WILLIAMSON, OF NEWPORT NEWS, VIRGINIA.

MACHINE FOR BLADING TURBINE-ROTORS.

1,172,385.

Specification of Letters Patent. Patented Feb. 22, 1916.

Application filed July 23, 1914. Serial No. 852,713.

To all whom it may concern:

Be it known that I, JAMES WILLIAMSON, a citizen of the United States, residing at Newport News, county of Warwick, State of Virginia, have invented a new and useful Machine for Blading Turbine-Rotors, of which the following is a specification.

My present invention consists of a novel machine which is especially designed for inserting the blades and distance pieces in the rotors of turbines, whereby the blades and distance pieces are assembled with respect to the rotor in a very expeditious manner and with a minimum amount of time and labor.

It further consists of a novel construction and arrangement of a motor which is connected in a novel manner with respect to a novel construction of a cross-head.

It further consists of a novel construction of a blade or hammer and novel means for operating the cross-head to cause said blade or hammer to travel in parallelism with the groove of the rotor in which the blades are to be inserted.

It further consists of a novel construction and arrangement of guides.

Other novel features of my invention will more clearly hereinafter appear in the detailed description thereof.

For the sake of illustrating one manner of carrying out my invention in practice, I have shown herein one form thereof, which will be found to give satisfactory and reliable results, although it is, of course, to be understood that the various instrumentalities of which my invention consists can be variously arranged and organized and that my invention is not limited to the precise arrangement and organization of these instrumentalities as herein set forth except by the scope of the appended claims.

Figure 1 represents, in side elevation, a machine for blading turbine rotors embodying my invention, and illustrated in assembled condition with respect to a sectional view of a rotor. Fig. 2 represents a sectional elevation of a portion of a rotor and a blade in conjunction therewith. Fig. 3 represents a front elevation of my novel machine. Fig. 4 represents a sectional elevation of a portion of my device. Fig. 5 represents an end elevation of a cross-head, piston-rod, and certain of their adjuncts. Fig. 6 represents a section on line $x-x$ of Fig. 4. Fig. 7 represents a sectional elevation taken through the cross-head. Fig. 8 represents a sectional

elevation of the motor. Fig. 9 represents a longitudinal section of the valve mechanism. Fig. 10 represents a transverse section of the valve mechanism.

Similar numerals of reference indicate corresponding parts in the figures.

Referring to the drawings:—1 designates a frame-work or casing, the contour of which may vary widely in practice, and in said casing is journaled, in any desired manner, the trunnions 2 carried by the motor-cylinder 3, which latter is provided with a cap or closure 4 secured thereto by means of fastening devices 5. The closure 4 is provided with a recess 6 and a groove 7, which latter communicates with a passage 8, said passage communicating with a conduit 9 leading to a valve-mechanism 10. The bore 11 of the motor has mounted therein a reciprocating piston 12, the piston rod 13 of which passes through a closure 14, which covers the forward end of the casing or cylinder 3, the latter being flanged, as best seen in Fig. 8, whereby the arms of a guide-bracket 15 are secured to the end of said cylinder 3 by means of fastening devices 16, which latter also pass through the closure 14 and the flanged end of the cylinder 3.

17 designates a stuffing-box carried by the closure 14 in any desired manner.

18 designates a groove in the closure 14 which communicates with a passage 19 in the cylinder 3, said passage 19 also communicating with a conduit 20, which leads to the valve 10. The valve 10 is provided with a main inlet port 21, which is adapted to be connected in any desired manner to the motive fluid supply and any desired type of motive fluid may be employed, one example of which is compressed air.

The valve body is provided with a conical seat 22, with which engages the conical wall of the valve-plug 23, the shank of which is provided with a flanged sleeve 24, which is retained in place by means of a cap 25 in threaded engagement with the valve body. The valve plug is provided with a longitudinally extending passage 26 which communicates with a transversely extending passage 27, which extends through the wall of the valve plug and is adapted to register with a port 28, which communicates with the conduit 20, or with the port 29, which communicates with the conduit 9. The side wall of the valve plug is recessed as at 30, in order that the port communicating with the cham-

ber formed by such recessed portion of the valve will alternately communicate with the exhaust port 31.

In order to limit the rotation of the valve plug, the inner end thereof is recessed, as at 32, thereby forming the walls 33 and 34, which are adapted to contact with a stop 35, comprising in the present instance, a bolt in threaded engagement with the valve body, 10 and provided with a lock nut 36. The stem of the valve plug is preferably faced off in order to receive a suitable actuating wrench 57. The valve body is provided with the apertured extensions 37 in order that it may 15 be secured to a suitable support, and in the present instance, this support is formed by brackets 38 carried by the frame-work 1 in any desired manner, and having their outer ends connected by means of a bolt and 20 nut 39.

The piston-rod 13 is connected to a cross-head 40 by means of a cross-head pin 41 carried by said cross-head. The cross-head pin 41 passes through a journal box 42, 25 which latter is secured to the flanged outer end of the piston rod 13 by means of fastening devices 43 of any desired type. The cross-head 40 is recessed on opposite sides, as indicated at 44, and is provided with gibs 30 45, which are secured in position by means of fastening devices 46, and the inner faces of said gibs slide on the guides 47, which are secured to the side brackets 38 by means of 35 fastening devices 48. The engaging faces of said gibs and guides are concentric to the groove 49 of a rotor 50, in which the turbine blades 51 and the distance pieces 52 are to be 40 inserted, and said groove is cut away, as at 53, in order that the blades and distance pieces may be inserted therein. In practice, 45 a plurality of slots, such as 53, are formed, so that after the turbine blades and distance pieces have been inserted and assembled for a portion of the periphery, the rotors can then be moved into proper position 50 for the insertion of a desired number of turbine blades and distance pieces without the necessity of moving the machine. The groove 49 may have any desired contour, but 55 in the present instance, the side walls are reversely inclined, as best seen in Fig. 2. The cross-head 40 is provided with an aperture 54 therethrough, thereby adapting the same to receive the pressing or working tool 55, which is retained in position by means of a set screw 56.

The operation of my novel machine for blading turbine rotors will now be readily apparent to those skilled in this art, and is 60 as follows:—The machine and the rotor are arranged in such a manner that the groove 49 and the side walls of the guides 47 are concentric to each other. Assuming that the piston 12 is at the rear end of the cylinder of 65 the motor, a desired number of the turbine

blades and distance pieces are inserted through a slot or opening 53 into the rotor groove, the tool 55 being positioned in rear of the blades and distance pieces. The operator then actuates the valve plug 23 to 70 bring the passage 27 into register with the port 29, whereupon live motive fluid may pass through the conduit 9, passage 8, and groove 7, into the piston chamber 11, in rear of the piston 12, and cause the same to move 75 forwardly. This causes the cross-head 40 to be moved forwardly and the bar 55 will impart a uniform pressure to the blades and distance pieces which have been inserted, until the forward one abuts against a stationary stop, which has been previously located in a groove 49. During this forward movement, the forward end of the tool 55 is seated in the groove 49 and moves in the arc of a circle, owing to the novel manner in 80 which the cross-head is guided. The exhaust in front of the piston 12 takes place through the passage 19, conduit 20, port 28 of the valve casing chamber 30, and exhaust port 31. The valve plug 23 is then rotated 90 to permit the live motive fluid to pass through the passage 27, port 28, conduit 20, and into the piston chamber 11 in front of the piston 12 and cause the same to be moved rearwardly, the exhaust in rear of the piston 95 taking place through the groove 7, passage 8, conduit 9, port 29 of the valve, casing chamber 30 and exhaust port 31.

In the methods heretofore employed for securing turbine blades and distance pieces 100 in grooves or rotors, the distance pieces and turbine blades have been inserted separately into a groove and calked in place by hand, the result of which is that rectifying of the blades and distance pieces is necessary, and 105 such operation is expensive as it involves a considerable amount of manual labor and time.

In accordance with my present invention any desired number of blades and distance 110 pieces may be inserted in a turbine groove, and simultaneously pressed into position, or upset within a groove, this result being accomplished by actuating the valve handle 57. A wedge is first inserted in the groove to 115 form an abutment for the first blade, and after the blades and distance pieces have been secured in the groove in proximity to one of the slots 53, the rotor 50 is partially rotated in order to bring the next slot 53 into 120 the proper position for the insertion of additional turbine blades and distance pieces, and so that the tool 55, when at the end of 125 its rearward stroke, will be in rear of the slot 53. The operation is thus repeated until an entire turbine groove is filled, it being understood that the wedge is removed and the space filled with turbine blades and distance pieces to complete the ring or 130 crown of blades.

In accordance with my present invention, there is no likelihood of the binding of the blades and distance pieces, while being advanced or moved forward by the tool or impact member, which is reciprocated by the piston, since, although the piston and piston rod are reciprocated in a rectilinear path, the tool or impact blade and the cross head are reciprocated in a curvilinear path, which is concentric to a turbine groove.

Special attention is directed to the novel manner in which the pressing tool is supported and guided during its reciprocating travel, so that its pressure is exerted in a curvilinear direction.

I am aware that it has heretofore been proposed to employ a pressing tool which is reciprocated in a path substantially tangential to a turbine groove, but my present invention is clearly differentiated from such a construction, since the pressing tool in my invention is reciprocated in a curvilinear path, substantially concentric with the turbine groove, the free end of said tool traveling in a circular path having the rotor axis as its center, and to none of the constructions of the prior art do I herein make my claim.

It will now be apparent that I have devised a novel and useful construction of a machine for blading turbine rotors which embodies the features of advantage enumerated as desirable in the statement of the invention and the above description, and while I have, in the present instance, shown and described a preferred embodiment thereof which will give in practice satisfactory and reliable results, it is to be understood that the same is susceptible of modification in various particulars within the scope of the appended claims without departing from the spirit or scope of the invention or sacrificing any of its advantages.

Having thus described my invention, what I claim as new and desire to secure by Letters Patent, is:—

1. A device for securing blades in turbine grooves of rotors, comprising a cross-head, means to reciprocate said cross-head in a curvilinear path concentric with a turbine groove, a tool fixedly carried by said cross-head and adapted to extend into a turbine groove whereby said tool is caused to travel in a path concentric with the axis of the rotor.

2. A device for securing blades in turbine grooves, comprising a stationary frame, a reciprocating motor pivotally mounted thereon, a cross-head operatively connected with said motor, a tool carried by said cross-head, reciprocating means for said motor, and guiding means for said cross-head to cause the free end of said tool to travel in a path concentric with a turbine groove.

3. A device for securing blades in turbine

grooves, comprising a stationary frame, a reciprocating motor pivotally mounted thereon, and having a piston rod, a cross-head pivotally connected with said rod, a tool carried by said cross-head, means to reciprocate said piston rod in a rectilinear path, and means to guide said cross-head in a curvilinear path.

4. A device for securing blades in turbine grooves, comprising a stationary support, a reciprocating motor pivotally mounted thereon, and provided with a reciprocating piston and piston rod, a guide for said piston, means to reciprocate said piston, a cross-head movably connected with said piston rod, a tool carried by said cross-head and extending into a turbine groove, and means to guide said cross-head to cause it to travel in a curvilinear path concentric with said groove.

5. A device for securing blades in turbine grooves, comprising a motor consisting of a casing pivotally supported, a piston in said casing and a piston rod, a cross-head connected with said piston, means to guide said cross-head in a curvilinear path, a tool adjustably carried by said cross head, means to fix said tool in its adjusted position, and means to introduce motive fluid to either end of said piston.

6. A device for securing blades and distance pieces in turbine grooves of rotors, comprising a pressing tool, means to cause said pressing tool to travel on the circumference of a circle having its center on the axis of the rotor, and means to adjust said pressing tool so that the end thereof will travel on the circumference of a circle of a different radius about the axis of the rotor.

7. A device for securing blades in turbine grooves, comprising a cross head having an aperture extending laterally therethrough, a tool in said aperture, means to fix said tool in adjusted relation with respect to said cross head, means to reciprocate said cross head, and means comprising a curvilinear guide for said cross-head and adapted to cause said cross head to reciprocate in the arc of a circle.

8. A device for securing blades in turbine grooves, comprising side brackets, guides secured thereto, and having their side faces curved to form guides, a cross head having recesses in the sides thereof, wear plates secured to said cross head and having curved faces to engage said guides, a tool laterally adjustable in said cross head, and means to reciprocate said cross head.

9. A device for securing blades in turbine grooves, comprising a cross head having an aperture therethrough, a tool adjustable in said aperture, a fastening device carried by said cross head and en-

gaging said tool to secure the latter in adjusted position, a piston rod pivotally connected with said cross head, a piston connected with said piston rod, and means to control admission of motive fluid to and exhaust of motive fluid from opposite sides of said piston.

10. A device for securing blades in turbine grooves of rotors, comprising a frame-work, a motor consisting of a casing having trunnions journaled in said frame-work, said motor including a reciprocating piston and piston rod, means carried by said casing to guide said piston rod, a cross head movably connected with said piston, means to control admission to and exhaust from opposite sides of said piston of motive fluid, a tool carried by said cross head, and means

to cause said pressing tool to travel on the circumference of a circle having its center 20 on the axis of the rotor.

11. A device for securing blades in turbine grooves, comprising a cross head having opposite sides thereof recessed, wear plates located in said recesses, guides having curved guiding faces on opposite sides thereof, with which said wear plates engage, means to adjust said wear plates with respect to said guides, a tool carried by said cross head, and actuating means for 30 said tool.

JAMES WILLIAMSON.
